FLASHLIGHT

Joseph G. Bacevius, Shelton, Conn., assignor to Paul G. Garrity, Stamford, Conn.

Filed Mar. 26, 1973, Ser. No. 344,941

Term of patent 14 years

Int. Cl. D26—02

U.S. Cl. D48—24 A

FIG. 2

FIG. 1

FIG. 4

FIG. 7

FIG. 1 is a side elevation view of a flashlight showing my new design.

FIG. 2 is a top plan view thereof.

FIG. 3 is a bottom plan view thereof.

FIG. 4 is a front elevation view thereof.

FIG. 5 is a rear end view thereof.

FIG. 6 is a side elevation view of the other side thereof.

FIG. 7 is a perspective view thereof.

The flashlight is shaded to indicate contrast.

I claim:

The ornamental design for a flashlight, substantially as shown and described.
